UNITED STATES PATENT OFFICE.

SAMUEL A. NELSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM FOR DROP-BOX LOOMS.

Application filed June 4, 1925. Serial No. 34,965.

This invention relates to a loom of the type in which a plurality of shifting shuttle boxes or drop boxes are provided at the weft replenishing or magazine end of the loom. This construction is most commonly found in the so-called "pick-and-pick" loom, in which a plurality of drop boxes are provided at each end of the loom and in which provision is made for inserting a single pick only of any desired color of weft at any desired point in the fabric. It has been found very difficult to transfer a bobbin to a shuttle in one of a set of vertically movable drop boxes, as the boxes are moving vertically at the time when they reach front center, at which point the transfer of the weft carrier commonly occurs.

It is one object of my invention to provide a construction by which a transferring device is movable vertically with the drop boxes as they rise and fall and in which the transerrer also has an independent vertical movement to a normal position of alignment with the running shuttle.

A further object of my invention is to provide mechanism for actuating the transerrer to insert a weft carrier as the transerrer moves with the drop boxes.

My invention further relates to arrangements and combinations of parts which will be hereinafter described and more particularly pointed out in the appended claims.

A preferred form of the invention is shown in the drawings, in which—

Fig. 1 is a right hand side elevation of parts of a loom embodying my improvements, with the magazine and drop boxes shown in section;

Fig. 2 is an enlarged side elevation of the weft carrier transerrer, together with mechanism for supporting and actuating the same;

Fig. 3 is a front view of the parts shown in Fig. 2;

Fig. 4 is a top plan view of the parts shown in Fig. 2, with the magazine omitted;

Fig. 5 is a sectional plan view, taken along the line 5—5 in Fig. 3;

Fig. 6 is a detail side elevation of a revoking device;

Fig. 7 is a detail front elevation, looking in the direction of the arrow 7 in Fig. 6;

Figs. 8 and 9 are partial side elevations, illustrating the operation of the invention

and showing the parts in different successive positions, and

Fig. 10 is a sectional view taken along the line 10—10 in Fig. 5.

Referring to the drawings, I have shown a loom frame 20 (Fig. 1) on which a lay 21 is pivotally mounted for oscillation through a crank arm 22 from the usual crankshaft 23. A set of shifting shuttle boxes or drop boxes 24 are mounted for vertical movement at the right hand end of the lay 21 and a similar set of shifting boxes is mounted for vertical movement at the opposite end of the lay (not shown).

A weft carrier magazine 25 is mounted on the frame 20 at the weft replenishing side 70 of the loom and is shown as being of the stationary type and as provided with three weft carrier compartments 26 adapted to contain weft carriers or bobbins having different kinds of colors of weft thereon.

Any suitable and convenient mechanism may be provided for shifting the drop boxes vertically in accordance with the demands of the pattern and also for selecting and releasing the desired weft carriers from the magazine 25. The shuttles S in the boxes 24 are of the type which permits insertion of a bobbin or weft carrier from the side, as shown in the prior patent to Crompton, No. 739,651, issued September 22, 1903.

I will now describe the mechanism by which I transfer a bobbin from the magazine to the shuttle which is active at the time of transfer indication. For this purpose I provide a fixed stand 30 (Fig. 3) firmly mounted on the loom frame 20 and having bearings 31 and 32 for a pair of sliding rods 33. A movable frame is secured to the sliding rods 33 and comprises a lower member 34 and an upper member 35 joined together by vertically extending braces 36.

Coil springs 37 and 38 are mounted on each rod 33 between the plates 34 and 35 respectively and the corresponding upper stand bearing 31. Collars 39 are loosely 100 slidable on the rods 33 but are provided with cross pins 40 which extend through separate slots 41 in the rods to limit movement of the collars toward each other. The supporting frame is thus normally maintained in mid-position with respect to the stand 30 but may be yieldingly raised or lowered from such mid-position.

A bobbin-holding carrier is mounted to slide forward and rearward in the supporting frame and comprises a lower member 42 and an upper member 43 joined together by 5 upright braces 44 (Figs. 3 and 5). On its upper face the member 43 is provided with a pocket or recess 45 to receive a bobbin B, as indicated in dotted lines in Fig. 3. The plates 42 and 43 of the bobbin-holding carrier are preferably slidable on dove-tailed 10 guide-ways on the plates 34 and 35 of the supporting frame, as clearly indicated in Fig. 3.

A transerrer slide 50 (Fig. 5) is mounted 15 to slide forward and rearward in the lower plate 42 of the bobbin holding carrier and provides a bearing 51 for a transerrer 52. An arm 53 (Fig. 2) extends upward from the slide 50 and is provided with an adjustable stop screw 54 engaging the transerrer to limit forward movement thereof. A tension spring 55 holds the transerrer yielding 20 against the screw 54.

A rod 56 (Fig. 5) is secured to the lower 25 part of the slide 50 and extends through a bearing in the front end of the plate 42. A nut 57 threaded on the end of the rod 56 limits rearward movement of the slide relative to the plate 42. A heavy coil spring 58 surrounds the rod 56 and normally holds the slide 50 in its adjusted rearward position.

This yielding construction provides a give-way which permits the transerrer to slide forward in the bobbin holding carrier 30 if a misplaced bobbin or shuttle prevents normal movement of the transerrer, otherwise the slide remains at its adjusted rearward position during all operations of the loom.

The transerrer 50 is provided with a laterally extended head 59 at the upper end thereof, as best shown in Fig. 4. The head 59 is positioned to swing forward and rearward in the pocket or recess 45 which receives the bobbin from the magazine.

A pair of spring plungers 60 and 61 (Figs. 2 and 3) are mounted near the rear end of the pocket 45 and have upwardly projecting portions 62 (Fig. 2) which yieldingly engage the butt and tip of the bobbin respectively and prevent the bobbin from rolling rearward out of the bobbin holder before the moment for transfer occurs. Nuts 63 (Fig. 3) provide adjustment for the yielding stops 55 or spring plungers 60 and 61.

I will now describe the provision for moving the bobbin holding carrier forward and rearward in its frame or support. A reciprocating bar 65 (Fig. 1) slides upon a support or bearing 66 and is pivoted at its rear end to the lower end of the lever 67 which in turn is pivoted at 68 to the loom frame 20. A roller 69 on the lever 67 is positioned in the cam groove or track of a side face cam 65 mounted on the crankshaft 23.

A control rod 71 (Fig. 3) is provided with a roll 72 normally positioned above the front end of the reciprocating bar 65, (Fig. 1). The control rod 71 is connected to suitable weft detecting mechanism (not shown) 70 at the opposite side of the loom and is withdrawn from its position above the bar 65 upon indication of weft exhaustion.

A lug 75 (Fig. 2) is formed at the lower rear edge of the carrier plate 42, and the reciprocating bar 65 is provided with a notch or recess 76 adapted to receive the lug 75. A tension spring 77 (Fig. 1) holds the bar 65 yieldingly against the roll or sleeve 72 on the rod 71.

When the control rod 71 is withdrawn by the detecting mechanism, the notch 76 in the bar 65 engages the lug 75 upon the next forward movement of the bar and draws the bobbin holding carrier rearward. The front end 78 (Fig. 1) of the bar 65 engages a bracket 79 on the carrier plate 42 as the bar moves forward and thus returns the bobbin holding carrier to forward position.

The drop box lifter rod 80 (Fig. 1) is provided with a series of studs 81 on the side thereof and with a series of plungers 82 on the front thereof. A forked lever 83 is pivoted at 84 (Fig. 2) on a bracket 85 which in turn is mounted on the lower member of the stand 30.

A segmental gear arm 86 is formed on the hub of the forked lever 83 and a corresponding segmental gear arm 87 is pivoted at 88 on the bracket 85 and is provided with a forwardly extending arm 89 which has a pin and slot connection with a lifter rod 90. The rod 90 is threaded into a depending portion 91 of the member 34 of the supporting frame in which the bobbin holding carrier is slidable.

With these connections, it will be evident that swinging movement of the forked lever 83 will cause a corresponding raising or lowering of the bobbin holding carrier and its supporting frame. In the operation of my invention, the bobbin holding carrier is normally maintained in mid-position with its bobbin holding recess in alignment with the running shuttle in whichever box it may be located.

As the lay moves forward, the stud 81 on the drop box lifter rod 80 which corresponds to the shuttle box containing the running shuttle is received within the forked arms of the lever 83. If the lifter rod thereafter moves vertically to change the boxes during the transfer operation, the lever 83 will be swung upon its pivot 84 and will act through the connections described to raise or lower the supporting frame and the bobbin holding carrier, thus maintaining the transerrer and bobbin in alignment with the shuttle box containing the indicated shuttle.

If desired, the forked rear end 92 (Fig. 2) of the lever 83 may be yieldingly connected thereto, permitting the parts to yield slightly as the stud 81 reaches its extreme forward position.

Whenever the control rod 71 is withdrawn by the weft detector, causing the bobbin holding carrier to be drawn rearward by the rod 65, the lower end 94 (Fig. 1) of the 10 transferrer 52 is engaged by one of the plungers 82 on the drop box lifter rod 80 and is swung upon its bearing 51 to force the bobbin rearward past the yielding plungers 60 and 61, thereby inserting the bobbin in 15 the exhausted shuttle and rearwardly ejecting the spent bobbin therefrom.

As the lower end 91 of the transferer is thus moved relatively forward, it soon engages a stud 96 (Figs. 2 and 3) on an arm 20 97 fixed on the short shaft 98 pivoted in a bearing 99 depending from the lever carrier member or plate 42. A second arm 100 is fixed to the shaft 98 and has a stud or projection 101 extending over a portion of the 25 sliding bar 65.

When the stud 96 is engaged by the transferer, the device described acts as a knock-off to lower the bar 65, disconnecting the 30 notch 76 from the lug 75 and preventing further rearward movement of the bobbin holding carrier and transferer.

The parts are thereafter returned to normal position by engagement of the front end 78 of the bar 65 with the bracket 79 of the 35 bobbin holding carrier. While the bar 65 is thus depressed, the rod 71 is released by the weft detector and returns to normal position, thereafter maintaining the bar 65 in depressed position.

I have also provided means for revoking the transfer in the event of a widely misplaced shuttle. For this purpose, I provide a revoking lever 105 (Fig. 6) having a plunger 106 adapted to enter a slot or opening 107 extending transversely through the shuttle S, when the shuttle is properly positioned in the shuttle box. If the shuttle is misplaced, the plunger 106 strikes the side of the shuttle and the revoking lever 105 is 45 swung forward to the position indicated in dotted lines in Fig. 6. A stud 107 (Fig. 7) projects from the side of the lever 105 and engages a latch 108 on the side of the reciprocating bar 65. As the lever is swung forward, the bar is depressed, releasing the lug 75 from the notch 76. Further rearward movement of the bobbin holder is thus prevented.

In Figs. 1, 8 and 9, I have indicated different steps in the operation of my weft replenishing mechanism. Fig. 1 shows the normal position of the parts, with the bobbin holding carrier and transferer located in normal position opposite the running shuttle.

Fig. 8 shows the position of the parts just after indication of weft exhaustion, with the running shuttle at the opposite side of the loom from the magazine, and with the roll 71 withdrawn, permitting the 50 bar 65 to rise and seat the lug 75 in the notch 76. As the lay 21 thereafter moves rearward, the dwell in the cam 70 (Fig. 1) permits the bobbin carrier to remain in 55 normal position long enough to receive the new bobbin, released from the magazine upon indication of weft exhaustion. As the lay 21 thereafter moves forward after the flight of the shuttle to the magazine side of the loom, the bobbin carrier is moved rearward to meet the lay and the stud 81 for the active box enters the forked end of the lever 83. The lay and carrier then advance together but the lay moves enough faster to advance the stud 81 in the fork of the 60 lever 83 until the corresponding lug 82 engages and operates the transferer 52.

In Fig. 9 the parts are shown in the position which they assume when the lay has started back from front center and the 65 transfer is substantially completed. In this figure, the drop boxes are indicated as moving downward to bring the upper box to running position, the movement at this point being half completed. Such movement has 70 caused the forked lever 83 to swing downward and has thus lowered the bobbin holding carrier and its supporting frame, maintaining the bobbin receiving pocket and transferer opposite the active shuttle box. 75

It will be noted that the necessary vertical movement of the bobbin holding carrier and transferer is substantially less than that of the drop boxes, as the transfer is completed before the drop boxes have completed their movement to their new position.

Having thus described my invention, the advantages thereof will be clearly apparent. Particular attention is called to the great 80 saving in time which results from movement of the transferer with the shifting shuttle boxes, as this combined movement permits transfer substantially at front center, and also permits the shuttle boxes to shift at the 85 same point in the loom operation, as is the normal procedure.

Having thus described my invention and the advantages thereof, I do not wish to be limited to the details disclosed, otherwise, 90 than as set forth in the claims, but what I claim is:

1. In a weft replenishing loom, a weft carrier transferer, a set of shifting shuttle boxes, actuating mechanism therefor, means 95 to give said transferer a transferring movement, and means to keep said transferer in operative alignment with a selected shuttle box during such transferring movement, in whatever position said box may be found. 100

2. In a loom, a set of shifting shuttle boxes, a transerrer, means to move said transerrer toward the boxes to insert a weft carrier therein, and means to move said transerrer bodily with said boxes if the boxes are changed during said transferring movement.
3. In a weft replenishing loom, a weft carrier transerrer, a set of shifting shuttle boxes, means to move said transerrer with said boxes during transfer, and means to give said transerrer a transferring movement toward said boxes.
4. In a weft replenishing loom having a weft carrier magazine, a set of drop boxes at the magazine end of the loom, and actuating mechanism therefor, in combination, a weft carrier transerrer, means to normally position said transerrer in substantially horizontal alignment with the running shuttle, and means to move said transerrer vertically to maintain such alignment if the boxes are changed during transfer and means to actuate said transerrer to transfer a weft carrier while the drop boxes are changing.
5. In a loom, a set of vertically shifting drop boxes, actuating mechanism therefor, a transerrer, and means to move said transerrer to insert a bobbin from the front in a shuttle in one of said boxes, while at the same time permitting said boxes to be shifted vertically by the drop box mechanism.
6. In a loom, a set of vertically shifting drop boxes, a carrier for a bobbin selected to be transferred, a transerrer, means to move said carrier and said transerrer vertically with said drop boxes during transfer, and means to move said carrier and said transerrer rearward to transfer the bobbin.
7. In a loom, a set of vertically shifting drop boxes, a carrier for a bobbin selected to be transferred, said carrier being mounted for movement toward and from said drop boxes and also for movement vertically with said drop boxes, a transerrer mounted on said carrier, and means to move said transerrer relative to said carrier to transfer a bobbin to a selected box while said boxes are moving vertically.
8. In a loom, a set of vertically shifting drop boxes, actuating mechanism therefor, a transerrer and means to move said transerrer to insert a bobbin from the front in a shuttle in one of said boxes, while at the same time permitting said boxes to be shifted vertically by the drop box mechanism, said transerrer being coupled to said boxes for vertical movement therewith during the act of transfer.
9. In a loom, a set of drop boxes, a bobbin holding carrier, a supporting frame in which said carrier is mounted for substantially horizontal movement, a fixed stand for said frame, a set of springs yieldingly positioning said frame and carrier with the bobbin-holding portion of said carrier normally in substantial horizontal alignment with the running shuttle, and means to move said frame against the tension of said springs to cause said frame to follow the shifting movement of the drop boxes during transfer.
10. In a weft replenishing loom, a weft carrier transerrer, a set of shifting shuttle boxes, means to move said transerrer with said boxes during transfer, means to give said transerrer a transferring movement toward a selected box, and means to revoke the transfer if the selected shuttle is displaced.
11. In a loom, a set of vertically shifting drop boxes, a lifter rod therefor, a series of studs fixed on said lifter rod, a forked lever making a pin and slot connection with a selected stud corresponding to the running shuttle as the boxes are moved forward, a bobbin holding carrier having a transerrer mounted thereon, and connections from said lever to said carrier through which said carrier is maintained in substantially horizontal alignment with the running shuttle during transfer, in whatever vertical positions said shuttle may be found.
12. In a loom, a vertically moving bobbin holding carrier, a slide on said carrier, and a transerrer pivoted on said slide, said slide being normally maintained in rearward position on said carrier but being yieldable forwardly to prevent breakage of parts if a weft carrier is misplaced.
13. In a loom, a set of shifting shuttle boxes, a transerrer, a connection between said boxes and said transerrer effective to maintain substantial alignment of said transerrer with a selected box during transfer, in whatever position said box may be found, and actuating devices for said transerrer having continuous operative relation to said transerrer during transfer and during such box movement.
14. In a loom, a set of vertically shifting drop boxes, a lifter rod therefor, a series of studs and a series of plungers on said lifter rod, corresponding to the number of boxes, a transerrer, and a device to position said transerrer vertically, said device being actuated by a selected stud, and said transerrer receiving transferring movement from the corresponding plunger on said lifter rod, and said stud and plunger maintaining cooperative relation with said device and transerrer during any shifting of the drop boxes which may occur during transfer.
15. In a loom, a stand, a supporting frame yieldingly mounted therein, a bobbin holding carrier slidable in said frame, co-acting springs normally positioning said frame and carrier vertically so that a bobbin in said carrier is substantially aligned horizontally with the running shuttle, and means to com-

press one or the other of said springs to yieldingly displace said frame and carrier in the direction of a drop box change which occurs during transfer.

5 16. In a loom, a set of shifting shuttle boxes, a bobbin holding carrier, and means to form a selective connection between said boxes and said carrier, and to thereafter move said carrier vertically to correspond to any vertical movement of said boxes occurring during transfer.

10 17. In a loom, a set of vertically shifting

drop boxes, a bobbin holding carrier, means to form a selective connection between said boxes and said carrier, and to thereafter move said carrier vertically to correspond to any vertical movement of said boxes occurring during transfer, means to move said carrier rearward during transfer, and means to release said carrier before the rearward movement of said boxes begins.

In testimony whereof I have hereunto affixed my signature.

SAMUEL A. NELSON.
